UNITED STATES PATENT OFFICE.

JOHANN BIENZ, OF BERNE, SWITZERLAND.

DEVICE FOR MANUFACTURING MINERAL WATER.

1,015,753.

Specification of Letters Patent. Patented Jan. 23, 1912.

Original application filed December 28, 1910, Serial No. 599,641. Divided and this application filed March 21, 1911. Serial No. 615,973.

To all whom it may concern:

Be it known that I, JOHANN BIENZ, a citizen of the Swiss Confederacy, and residing at Berne, Switzerland, have invented 5 certain new and useful Improvements in Devices for Manufacturing Mineral Water, of which the following is a specification.

My invention relates to a process of manufacturing mineral waters, as described in 10 my application for patent, filed on December 28th, 1910, Serial No. 599,641, of which application this is a division.

My invention consists in an apparatus for carrying out said process. This apparatus 15 is so constructed that water, preferably impregnated with carbonic acid, is introduced in such a manner into the bottles, that it must pass a device holding a tablet composed of a mineral salt, or a mixture of several mineral salts. This tablet is broken 20 into small pieces by the operation of certain elements of my new apparatus and is then dissolved by the water passing into the bottle, so that this water will become mineral 25 water.

In order that my invention be better understood, I have shown my new apparatus in the accompanying drawing, in which—

Figure 1 is an elevation, partly in section, showing one form of the apparatus and Fig. 2 a similar view, showing another form of the apparatus.

In Fig. 1, the numeral 1 designates a sheet metal basket or casing, which can be opened 35 at the front, containing a siphon bottle 2 of well-known construction. The casing 1 is provided with apertures, through which the amount of water in the bottle can be observed, and the casing also serves for protecting the person filling the bottle against 40 injuries, should the bottle break during the filling operation. A bar 3, whose upper bent end is formed with an eye 4, is attached to the side of the casing.

A sleeve-like member 5 having its underside open along its entire length surrounds the discharge pipe 13 of the bottle. Its upper side has two apertures, between which is arranged a plate 6 for stiffening the 45 sleeve. A part of the cap 23 passes through the top aperture in the upper side of the sleeve. Integral with, or affixed to the upper end of the member 5 is a ring 7, having a female screw thread, in which a screw

threaded spindle 9 carrying a hand-wheel 8 55 can be moved axially. The sleeve 5 terminates below in a right-hand and left-hand lug. To these two lugs is soldered a mouthpiece 10, having an axial bore 11 opening into a chamber 12 in the enlarged, recessed 60 top end of the mouthpiece, which is screwed into the eye 4 of the bar 3. A bushing 14, which extends into the chamber 12 and fits tight against the wall thereof, is pushed over the free end of the discharge pipe 13 65 mounted on the bottle 2, and is located between the right-hand and left-hand lugs of the sleeve-like member 5, to whose ends the mouthpiece 10 is soldered. In the bottom end of the bushing 14 is screwed a conical 70 nozzle 15, whose end projects somewhat beyond the edge of the bushing, whereas between the other end of the nozzle and the mouth of the discharge pipe 13 a packing ring 17 is arranged. A small tube 16, whose 75 one end passes through the packing ring 17 and whose other end is located over the duct 18 coaxial with it, is inserted axially in the nozzle. A port 19 passing through the end of the nozzle and located at right angles 80 both to the duct 18 and to the tube 16 is connected with both of these. Owing to the conical face of the nozzle and the removal of material from the inner end of the bushing a channel 20 leading around the 85 entire nozzle is formed. The tablet 21 is in the lowest part of the chamber 12 in the mouthpiece 10, and a packing ring 12^a is arranged on the face of the shoulder in the chamber 12 located at about the same height 90 as the top of the tablet. The tablet 21 is inserted from above into the mouthpiece 10 before the bottle 2 is put into the basket 1.

On the head 22 of the bottle is placed a cap 23 which serves as abutment for the 95 screw 9 and has two arms 24, between which a disk 25 having a peripheral groove is journaled eccentrically, the free end of the lever 26 mounted on the bottle being located in said groove. Attached to the disk 100 25 is a chain 27, whose last link is for engagement with a hook 28 attached to the casing 1. This chain is of such length that it can be hooked onto the hook 28, attached to the casing 1, only after the lever 26 has 105 been depressed by means of the disk 25.

The apparatus as described operates in the following manner: Assuming that all

the parts of the apparatus are in the position shown in the drawing and that a tablet has been inserted into the mouthpiece 10 after lifting the bushing 14, the screw 9 is then tightened, whereby the top end of the bar 3 is subjected to a tension. This is an iron bar and as all the other parts of the apparatus consist of metal and are not particularly thick, both the bar and the casing yield, so that the tablet is pressed against the end of the nozzle 15 and broken to pieces. The screw 9 is screwed so tight that the bushing 14 is pressed against the packing ring 12^a in the chamber 12. Water 15 impregnated with carbonic acid is then supplied through a tube to the mouthpiece 10, whereupon the lever 26 is depressed by means of the disk 25 and the chain 27 attached to the hook 28, so that the bottle 20 remains open during the filling operation. The tablet 21 is generally completely dissolved in the inflowing water, and in any event still undissolved large particles are prevented, due to the narrowness of the 25 ducts 18 and port 19 from being carried away by the water, so that only small particles can be carried away by the water before they have become dissolved and these 30 will subsequently be readily dissolved in the bottle. After the bottle has been filled, the screw 9 is turned back away from the cap 23, the member 5 is swung away from the head of the bottle and the latter removed from the casing 1. The mouthpiece 10 35 may then be charged with a new tablet.

The form of the apparatus represented in Fig. 2 is for filling bottles, whose necks are provided at their upper ends with an internal screw thread and which are closed 40 with an ordinary glass screw stopper. To this end, my apparatus comprises a screw-threaded stopper 29 adapted to be screwed into the neck of the bottle. The stopper is screwed so far into a bushing 30 that it 45 abuts against a partition 33 dividing the interior of the bushing into two parts. At the top side of this partition an annular flange 34 is left standing, adapted to receive the tablet. A second stopper 36 provided with a grip 39 is screwed into the bushing 30, a packing ring 36^a being provided between the top edge of the latter and the stopper 36. The stopper 29 is provided with an axial bore 31, from whose 55 top end two narrow ducts 32 branch off, which, like the bore 31, are connected with corresponding ports 33^a in the partition 33 opening into the chamber surrounded by the flange 34. The stopper 36 has a bore 60 37 in alignment with the bore 31, terminating at one end in the annular chamber 35, and at the other end in a duct 38 at right angles to the bore 37 and traversing the entire stopper 36. Screwed laterally to 65 the stopper 36 is a socket 40, in which is lo-

cated a coil spring 43 which with one end abuts against a disk 42 of elastic material, e. g., leather, serving as a valve and normally closing one end of the duct 38, and with its other end against a nut 44 in the 70 socket, which is closed by a cap 45. For using this form of my apparatus, the stopper 29 connected with the bushing 30 is screwed into the bottle, whereupon a tablet is placed within the flange 34, and then 75 the stopper 36 is screwed so far into the bushing 30 that the tablet is broken to pieces and the packing ring 36^a pressed firmly between the bushing and the stopper. The annular recess 35 not only makes room for 80 the broken tablet, but also affords sufficient surface to the water flowing through the bore 37 for dissolving and washing away the broken tablet. Water impregnated with carbonic acid is then introduced through 85 the duct 38. The valve 42 provided in the socket 40 is for compensating the pressure of the water or carbonic acid, in order that when the pressure becomes too great, no solid particles of the tablet will be forced 90 through the ports in the partition 33 and stop.

40' is a narrow outlet provided in the wall of the casing 40 for the escape of carbonic acid gas, which may enter said casing 95 past the valve 42.

I claim:

1. A device for manufacturing mineral water, comprising two members each provided with a bore adapted to be displaced 100 one relative to the other whereby a chamber of variable size is formed in communication with said bores adapted to receive a mineral salt tablet, and means for detachably connecting said device to a bottle. 105

2. A device for manufacturing mineral water, comprising two members each provided with a bore whereby a chamber of variable size is formed in communication with said bores adapted to receive a mineral salt tablet, and means for detachably connecting said device to a bottle, and means for displacing one member relatively to the other thereby breaking up said tablet in 110 said chamber. 115

3. A device for manufacturing mineral water, comprising a mouth-piece provided with an axial bore and a chamber, a sleeve-like member, a bushing attached thereto, said bushing being movable in said chamber 120 and adapted to be fitted to the spout of a siphon bottle, and means for axially moving the bushing in said mouth-piece. 125

4. A device for manufacturing mineral water, comprising a mouth-piece provided with an axial bore and a chamber, a sleeve-like member, a bushing attached thereto, said bushing being movable in said chamber and adapted to be fitted to the spout of a siphon bottle, and means for axially 130

moving the bushing in said mouth-piece, and a nozzle in said bushing, projecting beyond its inner end.

5. A device for manufacturing mineral water, comprising a mouth-piece provided with an axial bore and a chamber, a sleeve-like member, a bushing attached thereto, said bushing being movable in said chamber and adapted to be fitted to the spout of a 10 siphon bottle, and means for axially mov-

ing the bushing in said mouth-piece, and means on said sleeve-like member for holding the bottle open during the inflow of the water.

In testimony whereof I affix my signature 15 in presence of two witnesses.

JOHANN BIENZ.
